UNITED STATES PATENT OFFICE.

HARRY B. MYERS, OF CHEROKEE, KANSAS.

DESIGN FOR A MILITARY-SERVICE BADGE.

53,458.

Specification for Design.

Patented June 17, 1919.

Application filed October 25, 1918. Serial No. 259,725. Term of patent 14 years.

To all whom it may concern:

Be it known that I, HARRY B. MYERS, a citizen of the United States, residing at Cherokee, in the county of Crawford and State of Kansas, have invented a new, original, and ornamental Design for a Military-Service Badge, of which the following is a specification, reference being had to the accompanying drawing, forming part thereof.

The figure is a plan view of a "rejected

U. S. A. military service" badge, showing my new design.

I claim:

The ornamental design for a military service badge, as shown.

HARRY B. MYERS.
